(57) **CLAIM**

We claim the ornamental design for a tessellating board, as shown and described.

DESCRIPTION

FIG. 1 is a front view of one embodiment of a tessellating board of the present general inventive concept;

FIG. 2 is a rear view of the tessellating board of FIG. 1;

FIG. 3 is a top view of the tessellating board of FIG. 1;

FIG. 4 is a left side view of the tessellating board of FIG. 1;

FIG. 5 is a right side view of the tessellating board of FIG. 1; and,

FIG. 6 is a bottom view of the tessellating board of FIG. 1.
